[57] ABSTRACT

A sterilant package includes paper containing a compound having at least one —CH₂OR group wherein R is alkyl, in particular the compound is hexamethoxymethylmelamine. The compound is capable of releasing formaldehyde, upon heating, and is used to sterilize an article in the package.

8 Claims, No Drawings

U.S. Patent Dec. 2, 1975

3,923,154

STERILANT PACKAGE

This invention relates to a package, and more particularly, to a new and improved package for sterilizing articles.

In recent years there has been an increased interest in sterilizing packages which have incorporated therein a sterilizing agent. In this manner, a sterilized article may be directly removed from the package, without a sterilizing treatment, immediately prior to use thereof.

U.S. Pat. No. 3,630,348 discloses a sterilizing package having a paper wall which includes a thermosetting resin having methylol groups which are capable of releasing free formaldehyde. In such a package, special precautions must be taken to prevent curing of the resin, which derogates from the ability to release free formaldehyde, and/or prevent premature release of formaldehyde. Accordingly, there is a need for improvements in sterilizing packages.

The principle object of the present invention is to provide a new and improved sterilizing package.

In accordance with the present invention, there is provided a package which includes paper containing a compound having at least one $-\text{CH}_2-\text{OR}$ group capable of releasing free formaldehyde upon heating wherein R is alkyl, preferably lower alkyl (1 to 6 carbon atoms) and most preferably R is methyl.

The drawing is a simplified schematic diagram of an embodiment of a package of the present invention.

Referring to the drawing, there is shown a sterilant package 10, including an article to be sterilized 12 and paper 11 containing a sterilizing amount of hexamethoxymethylmelamine.

The paper contains the compound in a manner such that the compound is either internally incorporated therein or coated thereon. The compound is preferably internally incorporated within the paper.

The paper includes a sterilizing amount of the compound, and in general, the paper includes an amount of the compound sufficient to provide in or on the paper from about 0.1 % to about 20 %, by weight, of formaldehyde (CH_2O), and preferably from about 1 % to about 7 %, by weight, of formaldehyde. It is to be understood, however, that greater amounts could be used, but in general, the use of greater amounts does not have any beneficial effect. Similarly, lower amounts could also be used in certain applications. The choice of the optimum amount of compound to be incorporated into or onto the paper is deemed to be within the scope of those skilled in the art from the teachings herein.

The specific amount of the compound to be added to the paper will vary with the free formaldehyde content of the compound with the compound being added to the paper in an amount to provide the desired formaldehyde content. In general, the compound is added to the paper in an amount from about 0.3% to about 60 %, by weight, and preferably, in an amount from about 3 % to about 20 %, by weight.

In accordance with the preferred aspect of the present invention, the compound containing the CH_2-OR group(s) is incorporated internally into the paper during the paper making process. The compound is most conveniently added to the paper as an aqueous solution at the size press of the paper machine. In general, the aqueous solution includes from about 5 % to about 90 % of the compound. The incorporation of the compound into the paper during the paper making opera-

tion at the size press or during another portion of the paper making operation is deemed to be within the scope of those skilled in the art.

Alternatively, as hereinabove described, the compound may be coated onto the paper subsequent to the paper making operation by any conventional coating operation, such as, air knife, wire rod, etc.

The preferred compound for addition to the paper is hexamethoxymethylmelamine. The compound has been found to provide excellent sterilizing properties. In addition, a sterilant package including paper containing hexamethoxymethylmelamine is prepared without undue premature releasing of formaldehyde. In addition, the formaldehyde may be released without destruction of the paper substrate. Furthermore, the hexamethoxymethylmelamine may be added to the paper without special precautions; i.e., the sterilizing ability of the compound is not diminished under the conditions normally encountered in a paper making process.

The paper including the compound having at least one $-\text{CH}_2-\text{OR}$ group, preferably the paper includes hexamethoxymethylmelamine, is employed in the production of a sterilant package. The paper may be incorporated into a vapor-proof package, such as an aluminum foil package or a polyester package, either as a separate piece within the package or as an integral part of the package; e.g., as the inner wall surface of the package, in which case, the vapor proof barrier forms the outer wall surface of the package. In the case where the paper including, for example, hexamethoxymethylmelamine, is employed as a separate piece in the package, the paper may be employed as an inner sleeve or lining or as a wrapping for the article to be sterilized which is in the package.

Alternatively, the outer surface of the package may be comprised of a material having a low-vapor transmission level, such as, polyethylene, polypropylene, polyvinylidene chloride, etc. In this manner, the formaldehyde released from the hexamethoxymethylmelamine, within the package, may be eventually dissipated into the atmosphere, prior to opening of the package. The paper containing the hexamethoxymethylmelamine may be an integral part of the package; i.e., forming the internal wall surface or portion thereof, of the package, or may be present as a separate sheet within the package; e.g., as a wrapping for the article to be sterilized which is placed within the package.

The package, including the article to be sterilized and the paper containing hexamethoxymethylmelamine 50 may be formed and assembled as known in the art. The assembled package is then heated for a time and at a temperature sufficient to effect sterilization of the article by release of formaldehyde from the hexamethoxymethylamine. The time required for such sterilization 55 is inversely related to the temperature, with lower temperature requiring longer times. In addition, the time-temperature relationship is dependent on the amount of formaldehyde incorporated into the vapor. In general, the package is heated to a temperature of at least 60 95°F. and below the char point of the paper most generally, the sterilization temperature ranges from about 110°F. to about 260°F. and, preferably the sterilization temperature is from about 140°F. to about 210°F. The time required for effecting sterilization is generally in 65 the order of 1 second to 24 hours and most generally in the order of 1 hour to 16 hours, with the shorter times corresponding to the higher sterilization temperatures. It should be apparent that longer times could be em-

ployed, but generally such longer times have no beneficial effect. The choice of optimum times and temperatures is deemed to be within the scope of those skilled in the art from the teachings herein.

The invention will be further described with respect to the following examples, but it is to be understood that the scope of the invention is not to be limited thereby. Unless otherwise specified, all parts and percentages are by weight.

In the following Examples I and II, sterilizing capacity is tested using bacterial spores as test organisms. *Bacillus globigii* (1×10^6 and 1×10^8) spores on aluminium and paper are used in the test. After sterilization, the biological spore strips are assayed for viability in trypticase soy broth (TSB). The TSB tubes are examined for *B. globigii* growth over a period of four days of 37°C. incubation. Tubes showing no biological growth are inoculated with viable spores to assure that no bacteriostatic conditions existed and that the broth supported microbial growth.

The sheet of paper, in standard surgical grade, is impregnated with a 8% aqueous solution of hexamethoxymethylmelamine (CYMEL 301) containing 15% ethanol, through a size press at 135°F. temperature and the paper dried rapidly, (in the order of 1 to 2 minutes), in an oven maintained at 200°-215°F. The paper is prepared to have various amounts of the CYMEL 301 as expressed in the amount of available formaldehyde.

Two strips of paper prepared as above (2% inches $\times$ $\frac{1}{8}$ inches) are sealed in a gas tight foil package with the biological spore strips placed between the two strips of paper. The package is placed in hot air incubators or ovens as hereinafter reported.

EXAMPLE I

Percent Available Formaldehyde	Spore Survival After Indicated Exposure									
	30 min.		1 hr.		2 hrs.		4 hrs.		6 hrs.	
	60C	90C	60C	90C	60C	90C	60C	90C	60C	90C

± Indicates some samples showing complete inactivation of test spores.

+ Indicates no complete inactivation of test spores.

65

EXAMPLE III

The hexamethoxymethylmelamine impregnated paper (containing 1.42% formaldehyde) is wrapped around the following items, with the spore strip being within the wrapping. The wrapping is sealed in a polyester (MYLAR) bag. The resulting package is heated at 90°C. for three hours, and the results are as follows:

10

EXAMPLE III

Test Item	Spore Survival ⁽¹⁾
Electronic components	A
Scapel (handle of blade)	0/6
Thermometers (0-150C)	0/6
Eating utensils (spoons, forks, and knives)	0/6
Optics (microscope lens)	0/1
Tissue culture plates	0/2
Tissue culture flask	0/1
Tissue culture dishes	0/1
Controls	3/3

⁽¹⁾Number of positive samples over number of samples exposed.

The present invention is not limited to packaging of the hereinabove described items in that any one of a wide variety of articles may be sterilized in a package as hereinabove described.

The present invention is particularly advantageous in that the use of a paper impregnated with a compound containing at least one $-\text{CH}_2\text{OR}$ group capable of releasing formaldehyde upon heating, in particular, hexamethoxymethylmelamine, in a sterilant package, provides for improved sterilization, as indicated by either lower sterilization temperatures and/or shorter periods

of sterilization. In addition, the compound used for releasing formaldehyde is more stable; i.e., the compound is not readily susceptible to curing or condensation, which facilitates production. These and other advantages should be apparent to those skilled in the art from the teachings herein.

Numerous modifications and variations of the present invention are possible in light of the above teachings and, therefore, within the scope of the appended 55 claims, the invention may be practised otherwise than as particularly described.

What is claimed is:

1. A package, said package having paper therein treated with a sterilizing amount of hexamethoxymethylmelamine, said paper containing from 0.1 to 20%, by weight, formaldehyde, provided by the hexamethoxymethylmelamine, whereby upon heating a sterilizing amount of formaldehyde is released in the package to effect sterilization.

2. The package of claim 1 wherein the paper forms at least a portion of the interior surface of the package.

3. The package of claim 1 wherein the paper is separately placed in the package.

4. A package, said package including an article to be sterilized, said package having paper therein treated with a sterilizing amount of hexamethoxymethylmelamine, said paper containing from 0.1 to 20%, by weight, formaldehyde, provided by the hexamethoxymethylmelamine, whereby upon heating a sterilizing amount of formaldehyde is released in the package to effect sterilization.

5. The package of claim 4 wherein the outer wall surface of the package is vapor proof.

6. The package of claim 5 wherein the paper is a wrapping around the article in said package.

7. The package of claim 4 wherein the outer wall surface of the package has a low vapor transmission level.

8. The package of claim 7 wherein the paper is a wrapping around the article.
